LIGHT RESTRICTING DEVICE

John B. Bartow, Blue Bell, Pa., assignor to Bartow Beacons, Inc., Philadelphia, Pa., a corporation of Pennsylvania

Application September 15, 1942, Serial No. 458,395

7 Claims. (Cl. 240-1)

This invention relates to light-restricting devices, and more particularly to a novel device for blackout or dimout purposes. While the device may be adapted for use with any light source, such as ordinary house lights, it is particularly useful in conjunction with emergency signal devices, commonly known as "flares."

There are now in common use electrically operable emergency signal devices, or "flares" which, when once set into operation, cannot be turned off. An example of such a device is shown in U. S. Patent No. 2,118,996. Devices of this character are sold and shipped in packages and it is desirable to be able to include several such devices in a single package. There is, therefore, an urgent need for a light-restricting device which may be used in conjunction with such an emergency signal device during a blackout, and which may be packaged with the latter without imposing any limitation on the desired multiple packaging of such signal devices.

One object of the present invention is to provide a novel light-restricting device of the character described hereinafter.

Another object of the invention is to provide an inexpensive and highly efficient light-restricting device which is particularly adapted for use in conjunction with emergency signal devices of the above-mentioned character, although not limited to such use.

A further object of the invention is to provide a light-restricting device which may be formed of inexpensive semi-rigid opaque material such as stiff paper or cardboard.

Other objects and features of the invention will be apparent hereinafter.

In the accompanying drawings:

Fig. 1 is a perspective view of one form of the light-restricting device;

Fig. 2 is an elevational view showing the device in position upon an emergency signal device of the type shown in the above-mentioned patent, the latter device being shown in dot-and-dash outline;

Fig. 3 is a sectional view taken along line 3-3 of Fig. 2;

Fig. 4 is a face view of the hood element of the light-restricting device prior to assemblage of the parts thereof;

Fig. 5 is a perspective view of a composite mounting and light-masking element prior to assemblage of the parts;

Fig. 6 illustrates the blank from which the element of Fig. 5 is formed;

Fig. 7 is a perspective view showing the parts 55, 2, 3 and 7, particularly the latter figure. Such

of the light-restricting device in association with a flare device of the above-mentioned character for packaging and shipping;

Fig. 8 is an elevational view of another embodiment of the light-restricting device in association with the flare device;

Fig. 9 is a side view of the same with one hood in raised position and with a portion of the device broken away for the sake of illustration;

Fig. 10 is an elevational view taken from the right side of Fig. 9;

Figs. 11 to 13 are fragmentary perspective views illustrating the operation of one of the hoods;

Figs. 14 to 16 are views supplementing Figs. 11 to 13, respectively, to illustrate the operation more clearly;

Fig. 17 is an exploded perspective view showing the two principal parts of the device;

Fig. 18 is a face view of the blank from which one part is formed;

Fig. 19 is a similar view of the blank from which the other part is formed; and

Fig. 20 is a perspective view of one of the spring elements employed in each hood.

Referring first to Figs. 1 to 7 of the drawings, there is illustrated one form of the light-restricting device which comprises two separable parts or elements, both of which are formed of a suitable semi-rigid opaque material such as stiff paper or cardboard. In Figs. 1 to 3, these two parts or elements are shown in assembled relation and are designated 1 and 2 respectively. Part 1 comprises a closed band or loop 3 which is preferably rectangular in shape for a purpose which will appear presently and which has integral tabs 4 and light-masks 5 integral therewith and extending therefrom. This part of the device is preferably formed from a blank such as shown in Fig. 6 having end tabs 6. The blank is folded or bent along the dot-and-dash fold lines and the ends are secured together to provide the finished part shown in Fig. 5. Ordinary wire staples shown at 7 in Fig. 5 may be employed to secure the ends together.

Part 2 of the device comprises a hood 8 secured to a strap 9. As shown in Fig. 4 the hood 8 preferably comprises a circular disk of cardboard or stiff paper or the like secured to member 9 of like material by means of ordinary wire staples 10. Member 9 has extending tabs 11 which may be inserted within the closed band 3 as illustrated in Fig. 1.

The light-restricting device is adapted for use with a flare device of the type shown in Figs. 2, 3 and 7, particularly the latter figure. Such

a device comprises a cylindrical casing 12 and an arch-shaped canopy 13 within which a small electric lamp (not visible) is disposed. Within the canopy 13 there is also a reflector (not visible) associated with the lamp and the light is emitted from both sides of the device through windows 14. As shown in Fig. 7, part 1 of the light-restricting device is adapted to snugly fit over the extended lamp housing or canopy of the flare device, with the tabs 4 resting upon the upper surface of the cylindrical casing 12. For shipping purposes, the part 2 may be wrapped about the flare device and removably secured thereto by means of a rubber band 15. From Fig. 7 it will be seen that the two-part light-restricting device may be packaged and shipped with the flare device without interfering in any way with the desired multiple packaging of such device mentioned above.

When it is desired to use the light-restricting device, the parts thereof are assembled on the flare device in the manner shown in Figs. 2 and 3, the member 9 setting upon and conforming to the shape of the lamp housing or canopy 13 and the tabs 11 being disposed within the closed band 3 to retain the hood part in place. The masks 5 may be solid throughout to eliminate entirely a direct light from the lamp or they may be provided with narrow slits 16 to emit a very small part of the direct light. Reflected light from the lamp is emitted on each side of the device through the semi-circular areas 17 which are not covered by the light masks. The tabs 4 cover the upper surface of the cylindrical casing 12 which might tend to reflect light upwardly. Thus these elements prevent such undesired reflection of the light. It will be seen, therefore, that the light-restricting device effectively eliminates all but a small portion of the emitted light and the light which is emitted is directed horizontally or downward and not upwardly.

Thus it will be seen that the above described form of the invention provides an inexpensive blackout device for an emergency signal device or flare which also lends itself nicely to packaging and shipping with the flare device and permits the desired multiple packaging of such device.

Referring now to Figs. 8 to 20, there is illustrated an alternative form of the light-restricting device in which the parts thereof are permanently secured together and the hood portions are movable between lowered and raised positions. This form of the device comprises two parts 18 and 19, as shown most clearly in Fig. 17, which correspond generally to the parts 1 and 2 of the previously described embodiment. Both of these parts are formed of a suitable semi-rigid opaque material, such as cardboard or stiff paper. Part 18 comprises a closed band 20 having integral tabs 21 and light masks 22 which serve the same purposes as the corresponding elements in the previously described embodiment. In this instance, however, part 18 has formed integrally therewith an arch member 23. Part 18 is preferably formed from a blank, such as shown in Fig. 18, which is folded along the dotted fold lines to obtain the structure shown in Fig. 17.

Part 19 comprises a central body portion 24 which fits over the arch member 23 and collapsible hood portions 25 and 26 on opposite sides of the said body portion. Each hood portion comprises a member 27 foldably hinged to the body portion 24 and foldable side sections 28 interconnecting member 27 and the sides of the body portion, as shown in Fig. 17. A spring element

29 in the form of a U-shaped piece of stiff wire, as shown in Fig. 20, is attached to each of the hood portions 25 and 26, as shown in dotted outline in Fig. 17. The spring element extends along 5 the edge portion of the hinged member 27 and along the edges of the adjacent side sections. As illustrated, the edge portions with which the spring element is associated are folded over the spring element and stapled as at 30, thus retaining the spring element in place. While the spring may be omitted, its presence is desirable for the reasons set forth hereinafter.

The parts 18 and 19 are permanently assembled by placing part 19 over part 18 and by stapling the two together as at 31 to provide the assembled device shown in Figs. 8 to 10. The assembled device is adapted to be placed over the projecting lamp canopy or housing of a flare device 32 of the type previously mentioned as shown 10 in Figs. 8 to 10. In Fig. 9, the light-restricting device and a portion of the lamp housing of the flare device are broken away to show the lamp 33 and the light-reflecting surfaces 34 and 35 which are employed in this type of flare device.

20 It will be seen from the above description and the illustration of Fig. 9 that the hoods 25 and 26 are individually movable from a lowered or collapsed position to a raised or extended position. In Fig. 9, hood 25 is shown in the lowered position, 25 while hood 26 is shown in the raised position. This collapsible hood structure enables the light-restricting device to be packed and shipped with the flare device while mounted thereon without interfering with the desired multiple packaging 30 of such flare devices, and it also enables control of the emitted light, as will be explained presently.

The spring element associated with each hood and the foldable side sections form a toggle or 40 over-center arrangement by means of which the hood is moved with a snap action to either of its positions in response to slight manual movement and is positively retained in either position. This action is illustrated in Figs. 11 to 16. In Fig. 11, 45 the hood 26 is shown in its extended or raised position and the toggle elements on one side are shown in Fig. 14. In Fig. 12, the hood has been moved toward its lowered position to a point where the toggle action is about to take place. 50 As shown in Fig. 15, the arms of the spring element are sprung outwardly and upon slight further movement of the hood toward its lowered position, the arms of the spring element move inwardly, forcibly collapsing the foldable sections 55 28 and moving the hood to its lowered position, as shown in Figs. 13 and 16. It will be seen that the foldable side sections function cooperatively with the spring element to effect the toggle action, the said sections forcing the arms of the spring 60 element outwardly during the initial movement and permitting the said arms to return during final movement. The same action takes place when the hood is moved from its lowered position to its raised position.

65 In packaging and shipping, the light-restricting device is placed on the flare device, as shown in Figs. 8 to 10, and both hoods are collapsed. In such condition, the light-restricting device does not interfere with the desired multiple packaging of the flare devices, as mentioned previously.

70 The light mask 22 on each side of the device is arranged to eliminate substantially all of the direct light from the lamp 33 so that only reflected light is emitted through the uncovered portions

of the windows on the opposite sides of the lamp housing. Of course, if desired, a narrow slit may be provided in each of the light masks as in the previously described embodiment. Each hood when raised functions cooperatively with the associated light mask to prevent the emitted light from being observed from above. In any instance, where it is desired to restrict the emitted light even further, one or both of the hoods may be lowered, thereby greatly decreasing the amount of emitted light. In the illustrated form of the device the hoods when lowered will shut off the light almost entirely. Of course, it is readily possible to design the device so as to vary the amount of light emitted with the hoods in either positions.

Although two embodiments of the invention have been illustrated and described, it will be understood that the invention is not limited thereto but is capable of other forms within the scope of the appended claims.

I claim:

1. A light-restricting device, comprising a semi-rigid band in the form of a closed loop adapted to embrace a portion of a light-emitting device, a light mask integral with said band and arranged so as to be disposed in the path of the emitted light, a collapsible hood carried by said band and adapted to effect different degrees of restriction of the light, and means operatively associated with said hood to effect snap movement of the same to its extended or retracted position whenever the hood is moved a predetermined amount toward either position.

2. A light-restricting device, comprising a semi-rigid band in the form of a rectangular closed loop adapted to embrace a portion of a light-emitting device, a pair of light masks on opposite sides of said band integral with said band and arranged so as to be disposed in the path of the emitted light, a pair of collapsible hoods carried by said band in cooperative relation with said light masks and adapted to effect different degrees of restriction of the light, and means operatively associated with each of said hoods to effect snap movement of the same to its extended or retracted position whenever the hood is moved a predetermined amount toward either position.

3. A light-restricting device, comprising a semi-rigid band in the form of a closed loop adapted to embrace a portion of a light-emitting device, a collapsible hood carried by said band and adapted to effect different degrees of restriction of the light, and means operatively associated with

said hood to effect snap movement of the same to its extended or retracted position whenever the hood is moved a predetermined amount toward either position.

5. A light-restricting device, comprising a semi-rigid band in the form of a closed loop adapted to embrace a portion of a light-emitting device, a pair of oppositely disposed collapsible hoods carried by said band and adapted to effect different degrees of restriction of the light, and means operatively associated with each of said hoods to effect snap movement of the same to its extended or retracted position whenever the hood is moved a predetermined amount toward either position.

6. A light-restricting device, comprising a semi-rigid band in the form of a closed loop adapted to embrace a portion of a light-emitting device, an arch member carried by said band, a collapsible hood supported by said arch member and adapted to effect different degrees of restriction of the light, and means operatively associated with said hood to effect snap movement of the same to its extended or retracted position whenever the hood is moved a predetermined amount toward either position.

7. A light-restricting device, comprising a semi-rigid band in the form of a closed loop adapted to embrace a portion of a light-emitting device, a collapsible hood carried by said band and having foldable side sections, said hood serving to effect different degrees of restriction of the light, and a U-shaped spring element secured to the main part of said hood and having its arms secured to the adjacent parts of the foldable side sections to effect snap movement of the hood to its extended or retracted position whenever the hood is moved a predetermined amount toward either position.

40 8. A light-restricting device, comprising a semi-rigid band in the form of a closed loop adapted to embrace a portion of a light-emitting device, a pair of oppositely disposed collapsible hoods carried by said band, each hood having foldable side sections and each serving to effect different degrees of restriction of the light, and a U-shaped spring element secured to the main part of each hood and having its arms secured to the adjacent parts of the foldable side sections to effect snap movement of the hood to its extended or retracted position whenever the hood is moved a predetermined amount toward either position.

JOHN B. BARTOW.
